CLAIM

The ornamental design for a sword shaped wall-mounted lamp, as shown and described.

DESCRIPTION

FIG. 1 is a perspective view of a sword shaped wall-mounted lamp showing the new design;

FIG. 2 is a front view thereof;

FIG. 3 is a rear view thereof;

FIG. 4 is the side view thereof; (both sides are identical); and,

FIG. 5 is the section view thereof; (top and bottom sections are shown).

The broken lines shown on the drawings are for illustrative purposes only and form no part of the claimed design.
